UNITED STATES PATENT OFFICE.

WILLIAM LOFTIE DENTON, OF SOUTHWICK, ENGLAND.

COMBINED BRUSH AND POLISHING-PAD.

1,369,404.

Specification of Letters Patent. Patented Feb. 22, 1921.

Application filed October 25, 1920. Serial No. 419,234.

To all whom it may concern:

Be it known that I, WILLIAM LOFTIE DENTON, subject of the King of Great Britain, residing at Southwick, Sussex, (whose post-office address is Seaford House, Southview Road, Southwick, Sussex,) England, have invented new and useful Improvements in and Connected with Combined Brushes and Polishing-Pads; and I do hereby declare the following to be a full, clear, and exact description of the invention, such as will enable others skilled in the art to which it appertains to make and use the same.

This invention relates to combined brushes and polishing pads more particularly intended for cleaning boots and shoes.

The object of the present invention is to provide an improved device of the above character in which the polishing pad is normally positioned within or against the body of the device when not in use.

According to this invention the polishing pad is in the form of a strip which is normally wound upon a spring controlled roller mounted preferably within the interior of the brush handle, the free end of the same extending out through a slot formed in the casing constituting such handle, means being provided to prevent the extremity of the pad from being drawn completely through the slot into the interior of the casing.

In use the pad strip is pulled out to its full extent and wrapped around the face of the brush in which position it is maintained by the pressure of the hand against the handle portion. Upon releasing the strip the same is automatically wound around its roller by the spring means aforesaid.

In order that the invention may be clearly understood a practical application of the same will now be described by aid of the accompanying drawings in which:—

Figure 1 is a side elevation in part section of a combined brush and polishing pad according to this invention.

Fig. 2 is an end elevation of the same.

Fig. 3 is a transverse section on the line 3—3 of Fig. 1.

Fig. 4 is a view similar to Fig. 2 but showing the polishing band fully extended and covering surface of lower brush.

The device illustrated in the drawings

comprises three brushes *a* *b* and *c*, the backs *a'* *b'* and *c'* of which are so arranged and secured together as to constitute a recess *d* which recess is completely inclosed by a metal covering plate *e*.

Disposed within the recess *d* is a roller *f* the pivots *g* of which are supported within recesses *h* formed in the backs *a'* and *c'* of the brushes *a* and *c*. The movement in one direction of the roller *f* is controlled by an axially disposed spring *i* the extremities *m* of such spring being connected to the roller and the adjacent brush back *c'* respectively.

The polishing band *j* is wound upon this roller and the free end *k* extends through a longitudinal slot *l* formed in the side of the metal covering plate *e*. The longitudinal edge of this free end *k* is constituted by a length of wire or its equivalent *m* the extremities *m'* of which extend on each side beyond the width of the slot *l* and operate as stops to prevent the band from being drawn completely in through the slot *l* into the interior of the recess *d*.

A ring or other handle *n* is provided to facilitate the withdrawal of the band from its roller.

In operation the band is withdrawn and wrapped around the face of the brush *b* as shown in Fig. 4 in which position it is maintained by the pressure of the fingers when holding the device for polishing.

Having now particularly described and ascertained the nature of my said invention and in what manner the same is to be performed I declare that what I claim is:—

In a combined brush and polisher, the combination of a hollow body of inverted U-shape cross section having its ends closed and provided with a longitudinal slit in one side, a brush head closing the bottom of the body, a spring roller within the body rotatably supported by the ends of said body, and a polishing strip wound upon the roller and adapted to be drawn through the slit for operative application across the brush head closing the bottom of the body.

In witness whereof I have signed this specification in the presence of two witnesses.

WILLIAM LOFTIE DENTON.

Witnesses:

GEORGE HUGHES,
T. HUGHES.
